UNITED STATES PATENT OFFICE.

PAUL BERLIN, OF HOBOKEN, NEW JERSEY, ASSIGNOR TO THE KNY-SCHEERER CORPORATION, A CORPORATION OF NEW YORK.

CROSS-BRIDGE X-RAY MACHINE.

1,273,812.

Specification of Letters Patent. Patented July 30, 1918.

Application filed July 14, 1916. Serial No. 109,251.

To all whom it may concern:

Be it known that I, PAUL BERLIN, a citizen of the United States, and a resident of Hoboken, county of Hudson, and State of 5 New Jersey, have invented certain new and useful Improvements in Cross-Bridge X-Ray Machines, set forth in the following specification.

This invention relates to electrical machines for therapeutic purposes, commonly called X-ray machines. The functioning purpose of the machine is to produce high-potential and uni-directional as well as oscillatory electric currents for therapeutic use.

15 The object of the present invention is to improve and make more reliable the rectifying commutator which forms a necessary part in a machine of the class described.

More specifically, the object of this invention is to minimize the difficulties arising 20 from the arc drawn out by the rotating parts of a high-potential rectifier. It has been found in practice that trouble is experienced from what is believed to be ionized particles 25 of a conducting character which collect or persist in a position or path to form a continuing conducting path after an interruption in the circuit is desired, provided there is present any part of the mechanism (even

30 though the same be of an insulating character) which will form a carrier or path former for the said particles. It is believed that centrifugal and centripetal forces and also the force governing charged particles control 35 the action of the ionized particles which give the trouble mentioned. A specific object of this invention is to design the rectifier in such a way that these various forces will tend to act in opposition one to another and result 40 in a quick disruption of the undesired arc. A further and more specific object of the invention is to design the apparatus so that a single insulating plate in the commutator structure will serve the double purpose 45 of effecting revolution of rectifying conductors and also serve as a positive insulating barrier between stationary parts of the rectifying mechanism.

The above will be better understood by 50 reference to the illustrative embodiments of the invention described and claimed herein in connection with the accompanying drawings which form a part hereof, in which like characters designate corresponding parts in

the several figures and in which Figure 1 is 55 a front elevation of an X-ray machine embodying the invention, with the doors removed; Fig. 2 is a vertical section with parts shown in elevation along the line II—II of Fig. 1; Fig. 3 is a still further enlarged detail section, with parts broken away, through line III—III of Fig. 2; Fig. 4 is a section, with parts broken away, through line 60 IV—IV of Fig. 3; Fig. 5 is a perspective view showing a modified form of the rotating part 65 of the rectifier; Fig. 6 is a diagrammatic view showing a rectifier which evidences in practice the arcing trouble which it is an object of this invention to overcome; and Fig. 7 is a diagrammatic illustration showing 70 the circuit connections in the present invention.

It is customary in machines of this character to employ an inverted rotary converter if direct current is the original source of supply, but to employ a synchronous motor if alternating current is the source of supply. If the synchronous motor is employed, both the motor and the primary of the step-up 75 transformer are connected directly to the source. If an inverted rotary converter is employed the alternating current windings are connected to the primary of the step-up transformer. The expression "motor element having alternating current windings" 80 is therefore employed to designate generally both the inverted rotary converter or a synchronous motor or its equivalent. The purpose of this interconnection between the 85 circuits to be rectified and the motor element would of course be understood as to maintain 90 synchronism between the rotating rectifier and the current wave to be rectified.

In the drawings, a suitable cabinet A is 95 provided to contain the various pieces of mechanism in a manner well understood in the art. B is a step-up, high-potential transformer and C is the electric machine comprising the motor element having alternating 100 current windings. D is the rectifying mechanism proper. The high-potential leads from the secondary of the transformer B are indicated by 1 and 2, while the delivery leads connected with the service terminals 3 and 4 are indicated respectively by 105 5 and 6. The potential sign of the leads 1 and 2 is alternating from plus (+) to minus (-) and from minus (-) to plus

(+), while it is desired that the leads 5 and 6 be respectively at all times either plus (+) for 5 and minus (-) for 6 or vice versa. The supporting frame 7, shown substantially square in construction, serves to mount the stationary conducting parts of the rectifier and may be of wood.

A pair of diametrically opposed receiving arcs 8 and 9 are suitably insulated and mounted by insulators 10 and 11 in the frame 7, preferably so that one is vertically above the other, arc 8 being connected to lead 1 and arc 9 being connected to lead 2. Intermediate the arcs 8 and 9 but axially separated therefrom is another pair of diametrically opposed conducting arcs 12 and 13 similarly insulated from and supported by the frame 7 through the medium of insulators 14 and 15, arc 12 being connected to delivery lead 5 and arc 13 being connected to delivery lead 6. In other words, the pairs of arcs 8-9 and 12-13 occupy respectively parallel planes, which planes are spaced apart axially along the imaginary axis passing through the centers of the circles of which the arcs form parts. It is preferable that, when viewed axially, the arcs overlap one another slightly, as best shown in Fig. 2, although this overlapping is not essential and may vary in degree. Thus each arc must be of an extent at least approximately 180 electrical degrees which, for the type of generator illustrated, necessitates an arc of at least approximately 90 mechanical degrees. The more the overlap of the arcs, that is, the more their extent greater than 90 mechanical degrees is, the greater is the portion of the current wave delivered to the X-ray tube. Approximately the middle of the overlapping portions of the arcs represents the peak of the current wave. The extent of each current wave delivered to the X-ray tube in electrical degrees is twice the number of mechanical degrees of arc-overlap plus twice the number of mechanical degrees beyond and before the overlap throughout which an effective cross-connection is maintained by the high tension arc which flows even when there is no overlap.

The shaft 16 from the motor element C is arranged axially of the arcs 8, 9, 12 and 13 and carries fixedly a rotary element 17 secured thereto by adjustable coupling 18. In Figs. 1, 2, 3, 4 and 7 this rotary element is an extensive insulating plate preferably in the form of a disk of mica board and of an extent to lap radially out a considerable extent beyond the radial extent of the arcs 8, 9, 12 and 13 so as to form a continuous insulating partition between the receiving arcs and the delivery arcs. By this means the insulating air gap between the axially separated arcs of opposite electrical sign is materially lengthened without axially increasing the separation of the arcs. In other words, by this

means, the axially separated arcs may be located quite close to each other without danger of the current arcing across. A pair of diametrically opposed cross-conductors 19 and 20 are mounted upon and extend through the disk 17 in a direction substantially parallel with the axis of rotation so that the same are caused to revolve about the axis of the shaft 16 when the disk 17 is rotated synchronously with the motor element. In this manner the receiving arc 9 is bridged, for example, to the delivery arc 12 when the receiving arc 9 is plus (+). At the same time the receiving arc 8 is bridged to the delivery arc 13 when the receiving arc 8 is minus (-). When the sign of the receiving arc 8 is changed to plus (+) the cross-conductor is in position to connect it to the delivery arc 12 and at this time the then minus (-) receiving arc 9 is connected to the delivery arc 13. It should be noted that these cross conductors are not aligned with the conducting arcs. The radius of the path of revolution of the cross conductors should preferably be not the same as the radius of the conducting arcs; in the drawings it is shown to be materially less. By this means any warping of the disk 17 cannot cause a cross conductor to collide with an arc as is the case when the cross conductors are aligned with the arcs. By this arrangement of parts very small clearance and consequently very small spark gaps permanently may be maintained between path of travel of the cross conductors and the arcs. This insures more power for the X-ray tube.

Illustrative circuit connections are shown in Fig. 7. The primary 25 of high-potential transformer B is to be understood as connected in circuit with the leads 26 of the motor element. The secondary 27 of transformer B has its plus-minus ($\pm$) lead 1 in connection with the arc 8 and its minus-plus ($\mp$) lead 2 connected with the arc 9. The delivery leads 5 and 6 are connected respectively with the arcs 12 and 13. In the position of the mechanism shown, the cross-conductor 19 is cross-connecting receiving arc 8 to the delivery arc 13 and cross-conductor 20 is connecting receiving arc 9 to delivery arc 12. A 90° revolution of the cross-conductor 20 to the position shown by the dotted circle 30 will cause the then minus (-) receiving arc 8 to be connected to the delivery arc 12 while the cross-conductor 19 has moved to the position 29 to cross-connect arcs 9 and 13 instead of 8 and 13.

It is, of course, to be understood that in high-potential rectification it is not necessary that the moving conductors of the rectifier physically contact with the stationary conductors of the rectifier, although physical contact may take place through the medium of flexible brushes. Satisfactory recti-

fication is accomplished when the moving conductors move only into close proximity with the stationary conductors.

In the apparatus illustrated, the disrupted circuit is actually broken between two stationary conductors which are axially separated one from another and preferably on opposite sides of the mica board disk. Any arc which is pulled out at the time a cross-conductor leaves a stationary conductor is subjected to a force tending to divert it and any ionized particles contained therein from the rotating parts of the apparatus. This is radically different from the action in apparatus such as shown in Fig. 6 in which an arc broken between the rotating conducting arc 31 and a stationary conductor 32 tends to sweep around the periphery 38 of the disk 33. It has been found that the ionized particles cling to this supposedly insulating surface and maintain the circuit indefinitely so that rectification is impossible.

In Fig. 5 is illustrated a modified structure in which a hub 40 is adjustably secured to the shaft 16 and carries cross-conductors 41 and 42 connected to insulating spokes 43 and 44. In other words, the disk 17 is omitted, whereas many of the advantages of the present invention are retained. The relative positioning of the cross-conductors 41 and 42 is the same as the positioning of the cross-conductors 19 and 20 with relation to the stationary arcs, and the circuit connections will of course remain the same.

The detail construction for the preferred form and mounting of the cross conductors 19 and 20 is shown in detail for the arc 19 in Figs. 3 and 4. Each cross-conductor comprises a central threaded stub 50 and two reduced end portions 51 and 52 on opposite sides of the disk 17 and preferably extending equi-distantly out therefrom. The extensions 51 and 52 are preferably oval in cross-section to reduce windage. Lock-nuts 53, 54, 55 and 56 firmly lock the cross-conductor to the disk 17 and readily permit lengthwise adjustment of the same relatively to the disk 17.

What is claimed and what is desired to be secured by United States Letters Patent is:—

1. In a high potential converting mechanism, a motor-element having alternating current windings; a pair of insulated diametrically opposed revoluble cross-conductors extensive in a direction parallel to their axis of revolution and of limited extent in their path of revolution; a pair of diametrically opposed insulated receiving arcs each spanning approximately at least 90 mechanical degrees and coöperable with the receiving ends of said cross-conductors; means for revolving said cross-conductors synchronously with said motor element comprising a plate of insulating material ex-

tending cross-wise to each conductor, in extent approximating at least one-half the length of said cross-conductor; a step-up transformer having a primary coil adapted to be connected in circuit with the alternating current windings of said motor-element and having a high-potential secondary coil in circuit with said receiving arcs; and a pair of diametrically opposed insulated delivery arcs intermediate and axially spaced out of the plane of said receiving arcs each spanning approximately at least 90 mechanical degrees and in coöperable relation with the delivery ends of said cross-conductors, whereby said cross-conductors operatively cross-connect said receiving arcs with said delivery arcs synchronously with the alternating wave in a manner to cause a non-alternating current to be available from said delivery arcs when the apparatus is energized from a suitable source of electric energy.

2. In a high-potential converting mechanism, a motor-element having alternating current windings; a pair of insulated diametrically opposed revoluble cross-conductors extensive in a direction parallel to their axis of revolution and of limited extent in their path of revolution; means for revolving said cross-conductors synchronously with said motor-element, comprising an extensive insulating plate extending radially beyond said cross-conductors an amount approximating at least one-half of the length of a cross-conductor; a pair of diametrically opposed insulated receiving arcs coöperable with the receiving ends of said cross-conductors; a step-up transformer having a primary coil adapted to be connected in circuit with the alternating current windings of said motor-element and having a high-potential secondary coil in circuit with said receiving arcs; and a pair of diametrically opposed insulated delivery arcs intermediate and axially spaced out of the plane of said receiving arcs and in coöperable relation with the delivery ends of said cross-conductors, whereby said cross-conductors operatively cross-connect said receiving arcs with said delivery arcs synchronously with the alternating wave in a manner to cause a non-alternating current to be available from said delivery arcs when the apparatus is energized from a suitable source of electric energy.

3. A high-potential rectifier comprising an insulating plate mounted to rotate on a central axis at right angles to the plane of said plate; a pair of diametrically opposed cross-conductors secured to and extending through said plate at positions a material distance radially inward from the rim of said plate approximating at least one-half of the length of a cross-conductor; a pair of diametrically opposed insulated

- receiving arcs mounted opposite one face of said plate adjacent to the path of travel of the receiving ends of said cross-conductors; and a pair of diametrically opposed insulated delivery arcs mounted opposite the other face of said plate intermediate the position of said receiving arcs and adjacent the path of travel of the delivery ends of said cross-conductors.
- 5 10. 4. A high-potential rectifier comprising an insulating disk mounted to rotate on a central axis at right angles to the plane of said disk; a pair of diametrically opposed cross-conductors secured to and extending through said disk; a pair of diametrically opposed insulated receiving arcs mounted opposite one face of said disk adjacent to the path of travel of the receiving ends of said cross-conductors; and a pair of diametrically opposed insulated delivery arcs mounted opposite the other face of said disk intermediate the position of said receiving arcs and adjacent the path of travel of the delivery ends of said cross-conductors, said arcs being located a material distance approximating at least one-half of the length of a cross-conductor toward the center from the periphery of said disk.
- 15 20. 5. In a high-potential rectifier for X-ray machines, two sets of conducting arcs occupying respectively displaced parallel planes; a rotatable member the rim portion of which, extending radially both outwardly and inwardly a material distance approximating at least one-half of the length of a cross-conductor beyond the radial position of said conducting arcs, is formed of sheet insulating material; and cross conductors extending through said rim of sheet insulating material, and mechanically attached thereto in coöperable relation with said conducting arcs.
- 25 30. 6. In a high-potential rectifier for X-ray machines, two sets of conducting arcs occupying respectively displaced parallel planes; a rotatable member the rim portion of which, extending radially both outwardly and inwardly a material distance approximating at least one-half of the length of a cross-conductor beyond the radial position of said conducting arcs, is formed of sheet insulating material, and mechanically attached thereto in coöperable relation with said conducting arcs.
- 35 40. 7. In a high-potential rectifier for X-ray machines, two sets of conducting arcs occupying respectively displaced parallel planes; a rotatable member the rim portion of which, extending radially both outwardly and inwardly a material distance approximating at least one-half of the length of a cross-conductor beyond the radial position of said conducting arcs, is formed of sheet insulating material, and cross conductors extending through said rim of sheet insulating material; and cross conductors extending through said rim of sheet insulating material; and cross conductors extending through said rim of sheet insulating material, and mechanically attached thereto in coöperable relation with said conducting arcs, whereby warping of said sheet material cannot cause a collision between a cross conductor and a conducting arc.
- 45 50. 8. In a high-potential rectifier for X-ray machines, two sets of conducting arcs occupying respectively displaced parallel planes; a rotatable member the rim portion of which, extending radially both outwardly and inwardly a material distance approximating at least one-half of the length of a cross-conductor beyond the radial position of said conducting arcs, is formed of sheet insulating material; and cross conductors extending through said rim of sheet insulating material, and mechanically attached thereto in coöperable relation with said conducting arcs, each cross conductor comprising a centrally threaded portion projecting through said rim and having clamping nuts on opposite sides of said rim whereby an adjustment in both directions of its length may be effected.
- 55 60. 9. In a high-potential rectifying switch for X-ray machines a cross conductor comprising a centrally threaded portion having at each end an extension having an air-cleaving configuration and clamping nuts for said threaded central portion.
- 65 70. 10. In a high-potential rectifier, two sets of stationary conducting arcs occupying respectively spaced parallel planes; a rotatable member mounted to rotate about the axis of said conducting arcs and comprising a plurality of cross conductors revolving in coöperation with said stationary conducting arcs and a mounting constraining said cross-conductors to occupy positions out of alinement with said conducting arcs, whereby incidental bending or warping of said rotatable member cannot cause a collision between such cross conductors and a conducting arc.
- 75 80. 11. In witness whereof I have signed my name to this specification, this 1st day of July, 1916.
